UNITED STATES PATENT OFFICE

163,318

FIREPLACE GRATE

Joseph J. Pentek, San Carlos, Calif.

Application June 10, 1950, Serial No. 10,460

Term of patent 7 years

(Cl. D81—18)

To all whom it may concern:

Be it known that I, Joseph J. Pentek, a citizen of the United States and a resident of the city of San Carlos, county of San Mateo, State of California, whose post office address is 121 Center Street, San Carlos, California, have invented a new, original, and ornamental Design for a Fireplace Grate, of which the following is a specification, reference being had to the accompanying drawings, forming a part hereof.

Fig. 1 is a view in end elevation of the fireplace grate embodying my new design;

Fig. 2 is a top plan view thereof;

Fig. 3 is a view in front elevation; and

Fig. 4 is a view in rear elevation of the fireplace grate of my design.

I claim:

The ornamental design for a fireplace grate, as shown.

JOSEPH J. PENTEK.
